UNITED STATES PATENT OFFICE.

FRED STEFFENS, OF ST. JOSEPH, MISSOURI.

CAR.

1,269,017.

Specification of Letters Patent. Patented June 11, 1918.

Application filed March 12, 1917. Serial No. 154,198.

To all whom it may concern:

Be it known that I, FRED STEFFENS, a citizen of the United States, residing at St. Joseph, in the county of Buchanan and State of Missouri, have invented a certain new and useful Improvement in Cars, of which the following is a specification.

My invention relates to improvements in cars.

10 It relates particularly to motor driven passenger cars and especially to street cars on which the fares are collected by a conductor.

One of the objects of my invention is to 15 provide a car which will be of neat design, of light weight and large seating capacity, which is adapted for easy and quick loading and unloading of passengers, which will be easy riding, well ventilated and comfortable, which will readily make sharp curves, and which will have a maximum tractive 20 and braking power.

A further object of my invention is an arrangement of the propelling motors such 25 that a maximum of power and tractive effort may be obtained therefrom, which will conserve energy, and which will greatly reduce the liability of the motor driven car wheels skidding or slipping.

30 My invention further provides a novel construction arranged so that the car body will be supported on three bearings only, whereby the car will be well balanced and cramping of the trucks in making turns will 35 be eliminated.

Still another object of my invention is to provide novel automatic registering means actuated by the passengers, and so arranged that each passenger before alighting from 40 the car will cause a registration of his presence on the car.

Another object of my invention is to provide on the car a conductor's station so located that the conductor may have a clear 45 view of the entire interior of the car and of the entrance and exit of the passengers.

50 My invention further provides novel and efficient means for supporting the car body upon the trucks, so as to prevent accident in case of breakage, while at the same time affording great flexibility with respect to the relative movement between the trucks

and the car body and furnishing a firm and easy riding support for the car body.

My invention provides further a novel 55 and efficient braking mechanism in which the brake shoes will have maximum braking power, which will afford a minimum of wear to the wheel tread and flanges, which will eliminate the picking up of snow and ice 60 by the brake shoes and reduce the liability of the brakes freezing.

My invention further provides a novel arrangement in the carrying of the brake cylinder, and novel means for compensating 65 for the wear of the brake shoes.

The novel features of my invention are hereinafter fully described and claimed.

In the accompanying drawings, which illustrate the preferred embodiment of my 70 invention,

Figure 1 is a side elevation of a car provided with my improvements.

Fig. 2 is an enlarged plan view of a portion of the same.

Fig. 3 is a plan view of the front truck and a portion of the body of the car.

Fig. 4 is a cross section on the line 4—4 of Fig. 3.

Fig. 5 is a vertical sectional view on the 80 line 5—5 of Fig. 3.

Fig. 6 is a plan view of the rear truck with some of the parts omitted.

Fig. 7 is a side elevation of the rear truck and a portion of the car body.

Fig. 8 is a cross section, partly broken away, on the line 8—8 of Fig. 6, some of the parts being omitted, and a portion of the car body being shown.

Fig. 9 is a vertical sectional view on the 90 line 9—9 of Fig. 6, some of the parts being omitted.

Fig. 10 is an enlarged fragmental plan view of a portion of one of the motors.

Fig. 11 is a plan view of a portion of the 95 rear truck and parts connected therewith.

Fig. 12 is an enlarged vertical sectional view, partly broken away, on the line 12—12 of Fig. 11, some of the parts being removed.

Fig. 13 is a horizontal section on the line 100 13—13 of Fig. 12, the car wheel being shown in plan.

Fig. 14 is an enlarged vertical sectional view on the line 14—14 of Fig. 11.

Fig. 15 is an enlarged vertical sectional view on the line 15—15 of Fig. 12.

Similar reference characters designate similar parts in the different views.

5 1 designates the car body provided with a low middle floor portion 2, an elevated front floor portion 3 and an elevated rear floor portion 4, see Fig. 1.

The car body 1 is provided near its forward end with two side entrances 5 and 6 separated by a transverse railing 7 and normally respectively closed by outwardly opening doors 8 and 9, as shown in Fig. 2.

The car body is provided near its middle 15 with two side exits 10 and 11, separated by a transverse railing 12 and normally respectively closed by outwardly opening doors 13 and 14, Fig. 2.

Immediately forward of the exit 10 is a 20 transverse railing 15, the inner end of which connects to the rear end of a longitudinal railing 16, which is parallel with and spaced apart from a conductor's desk or table 17, with which it forms a passage 18, which 25 connects the rear compartment with the compartment just forward thereof, the railing 15 serving as the dividing line or partition between the two compartments.

A suitable registering means is provided 30 in the passage 18, preferably one which is operable by the passengers going through the passage, and preferably consisting of a turnstile registering mechanism 19, which may be controlled by the conductor at his 35 station behind the table or desk 17, and which, without being operated, will not permit a passenger to pass from the forward compartment having the entrances 5 and 6 to the rear compartment having the exits 40 10 and 11. Any approved well known type of turnstile registering mechanism may be employed.

In the forward compartment, just referred to, and in alignment with the passage 45 18, may be a central longitudinal railing 20 which divides the compartment into two longitudinal sub-compartments, which communicate with each other at the ends of the railing 20.

50 Forward of the entrance 5 are two seats 21 which divide the compartment containing the railing 20 from a front compartment in which the motorman is located. Between the seats 21 is a passage 22 which may be closed by doors 23.

The different compartments may be provided with seats for the passengers arranged in any desired manner. In the drawing, the compartment containing the railing 20 60 is provided with two longitudinal seats 23 and 24 which are disposed respectively at opposite sides of the compartment. This arrangement permits the ready entrance of passengers and a large aisle space and room 65 for standing passengers. The rear compart-

ment may contain, as shown, all cross seats. Passengers after entering the car through the entrances 5 and 6 may pay their fare to the conductor as they pass through the turnstile 19 and occupy the more desirable 70 seats in the rear compartment. When the car is loaded to more than the capacity of the rear compartment, the passengers in the forward compartments, when they alight, will pass through the turnstile 19, after paying their fares, and then pass out of the car through the forward exit 10, thus not interfering in any way with the passengers in the rear compartment who may pass out through the exit 11.

When the car is nearly filled, passengers getting on may enter through the entrance 5, and pass from there through the passage 22 to the seats 21, when the doors or gates 23 are open.

The car may thus be quickly filled and emptied, the collection of each fare is assured, and the number of fares collected will be correctly registered.

The position of the conductor's station 90 is such that he can have a comprehensive view of the entire interior of the car and of the passengers entering and alighting.

The railings 7, 12, 15, 16 and 20 with their 95 supporting stanchions eliminate the requirements of straps to hang to and thus afford a desirable safety feature.

The doors 8, 9, 13 and 14 will, of course, be normally closed. The entrance doors 8 and 9 may be operated by the motorman, and the exit doors 13 and 14 by the conductor, any suitable well known mechanism being provided for this purpose. As the doors are closed, when the car is in motion, and as the entrance and exit floor 2 is but an ordinary step above the street level, and no hand holds are provided on the outside of the car, no person can be injured in trying to get on or off the car. Any suitable signaling mechanism, not shown, may be employed to inform the motorman when any of the entrance or exit doors are open. For the instruction of the passengers, suitable signs may be provided, although not shown, designating the entrance and the exit doors and the route of the car.

The car body 1 is carried on two trucks, three bearings being provided, one located centrally on the front truck and two located at the extreme outer sides of the car body 120 on the rear truck. The rear truck is designed to carry the greater portion of the load and to serve as the tractive or motor driven truck, and also as the truck to which the brakes are applied. Both trucks are 125 centrally pivoted to the car body. No weight is carried at the center of the rear truck, but all of the weight carried by the front truck is on one center bearing. This construction permits of very free action of 130

the front truck, thus enabling a long car to make sharp curves.

Referring particularly to Figs. 3, 4 and 5, 25 designates the two axles of the front truck provided with the usual car wheels 26, and mounted in boxes 27 located at the inner sides of the wheels 26 and supported upon a lower frame 28, and being slidably fitted in an upper frame 29, which is mounted upon coil compression springs 30, which are supported in pairs upon the boxes 27 respectively. Bolts 31 provided with nuts extend through the frames 28 and 29, boxes 27 and coil springs 30, for limiting the movement apart of the upper and lower frame.

15 A central king pin 32 extends through the floor of the body 1 and the frame 29. Encircling the king pin 32 is a series of balls 33 mounted between bearing members 34 and 35 which are respectively secured to the frame 29 and the car body 1. The front truck is located closely adjacent to the forward end of the car.

20 Referring particularly to Figs. 6, 7 and 8, 25 designates the two axles of the rear truck, which are provided each with two car wheels 37 and which are mounted in boxes 38 located respectively at the outer sides of said car wheels and which are mounted on a lower frame 39 which is secured to the lower ends and supported by vertical helical suspension springs 40, the upper ends of which are secured to and supported by an upper frame 41, which is supported by four pairs of vertical coil compression springs 42, said pairs being mounted respectively upon the boxes 38 which are vertically slidable in the upper frame 41.

25 For assuming the function of the suspension springs 40, in case that these springs should break, there are provided loose vertical chains 43, the lower ends of which are attached to the frame 39 and the upper ends of which are attached to the frame 41.

40 For supporting the car body 1 on the rear truck, the car body has secured to its under side, closely adjacent to its outer sides respectively two inverted curved channel bars 44, in which are adapted to run respectively two pairs of rollers 45, which pairs are respectively rotatably mounted on and supported by two oscillatable members 46 which are respectively pivoted on a horizontal axis to two blocks 47 by means of

55 two horizontal transverse bolts 48. The blocks 47 are mounted in a transverse channel bar 49, which forms part of the lower frame 39. For strengthening the frame 49, it is provided with two transverse brace bars 50 mounted on struts 51 carried by the channel bar 49 and having their ends extending through and respectively secured to the blocks 47.

60 The channel bar 49 is located at the middle of the rear truck and has extending

through it at its center a vertical king pin 52 which also extends through the frame 41 and the bottom portion of the car body 1. The inverted channels 44 are disposed concentric with the king pin 51 and serve as 70 tracks for the rollers 45.

The car body 1 is thus provided with two widely separated bearings on the rear truck, thus insuring stability, and its pivotal manner of support by means of these 75 bearings upon the rear truck affords great flexibility and permits the rear truck to readily assume different positions without cramping.

70 For propelling the car, I provide two electric motors 53, which may be of the usual type and which are respectively mounted on the rear truck at the forward sides of the rear axles 36. The motors 53 are provided with the usual armature driving shafts 54, 80 to which are respectively rigidly secured two pinions 55, which respectively mesh with two spur gear wheels 56 respectively rigidly secured to the axles 36. The rear sides of the casings of the motors 53 are respectively 90 pivotally supported on the axles 36, and their forward sides are respectively supported upon coil springs 57, Fig. 9, each set of which is supported upon a transverse bar 58, which in turn is supported by vertical 95 bolts 59, mounted upon the frame 41 and respectively encircled by coil springs 60, which are arranged to resist the upward movement of the motor casing.

90 By means of this manner of suspending the motors, when the driving shafts 54 are rotated so as to run the car forward, the pinions 55 will be rotated counter-clockwise as viewed in Fig. 9, and will exert a downward pressure on the axles 36, through the 100 intermediacy of the gear wheels 56, thereby exerting a downward pressure upon the car wheels 37 so as to increase their tractive effort. As the car is designed to always run with the same end at the front, a maximum of tractive power is obtained as compared with the usual construction in which the two motors are located either both between or both at the outer sides of the axles which they drive. The tractive effort is 105 further increased by reason of the rear truck being located so as to carry the greater portion of the load.

110 By reason of this manner of suspending the motors and the disposition of the rear truck so as to carry the greater portion of the load, the braking effort, which is exerted upon the rear truck wheels, will attain the maximum, and skidding or spinning of the wheels will be almost, if not entirely eliminated, thereby effecting a great saving in energy.

115 I will now describe the braking mechanism. Referring particularly to Figs. 11 to 15, 61 designates a braking cylinder, 120

which is mounted upon a horizontal plate 62, Fig. 11, which is secured to and supported by the upper frame 41, instead of being carried, as is the usual custom, by the car body. This way of supporting the braking cylinder is of great advantage in that it eliminates much of the old brake rigging and strain on the truck and car body. So far as I am aware, the braking cylinder has never been mounted directly upon the truck.

63 designates the usual piston rod, to which is pivoted one end of a lever 64, which is connected by a turn buckle 65 with a lever 66, one end of which is pivoted to the forward end of the cylinder 61. The forward end of said cylinder has connected to it a flexible hose 67, which conveys the operating fluid from the train pipe, not shown, to the cylinder 61. Two transverse horizontal bars 68, disposed respectively at the front and the rear of the axles 36, are respectively connected to the free ends of the levers 66 and 64 by two rods 69 and 70.

When the operating fluid enters the cylinder 61 through the hose 67, the piston rod 63 will be forced outwardly, thereby, through the intermediary of the turn buckle 65, swinging the free ends of the levers 64 and 66, toward each other, and thereby, by means of the rods 69 and 70, drawing the bars 68 toward each other, so as to set the brakes, as will now be described.

To each end of each bar 68 is connected the brake mechanism which operates upon the adjacent wheel 37. As each of these brake mechanisms is the same as the others, a description of one will suffice for all.

Referring particularly to Figs. 12 to 15, 71 designates two brake shoes which are disposed diametrically opposite the adjacent axle 36, and which are adapted to bear respectively upon opposite sides of a hub 72 with which the inner side of each wheel 37 is provided.

Each brake shoe 71 at its upper end is provided with two hooks 73, which embrace and are respectively pivotally supported by the two arms of an inverted T-shaped rod 74, which extends vertically through the upper frame 41 and has mounted upon its screw-threaded upper end a nut 75 which bears upon the upper side of a collar 76, Fig. 15, which has a rounded lower side resting in a recess provided in the upper side of a plate 77 which is supported upon the frame 41.

A spacing tube 78 encircles the rod 74 and bears at its lower end upon the hooks 73. The upper end of the tube 78 extends through a hole 79 in the frame 41 and bears against the plate 77.

Two levers 80 and 81 are respectively pivoted to the brake shoes 71 and have their lower ends respectively pivoted, below the

brake shoes 71, to the ends of a horizontal longitudinal turn buckle 82. The upper end of the lever 80 is pivoted to the adjacent end of the bar 68. The upper end of the lever 81 is pivotally connected to and supported by the frame 41.

When the bar 68 is moved to the right, as viewed in Fig. 12, the brake shoes 71 will be forced, through the intermediary of the turn buckle 82 and lever 81 against the hub 72, thereby applying the brakes.

The hub 72 is preferably provided with an annular peripheral groove 83, in which the two adjacent brake shoes 71 are pivoted, and thereby preventing movement of the 80 brake shoes laterally and in a direction parallel with the axle 36.

In order that the brakes may be manually operated, when desired, the piston rod 63 has attached to it a rearwardly extending 85 chain 84, Fig. 11, which is attached to one end of a lever 85, pivotally mounted on the frame 41 and having its opposite end pivoted to the rear end of a forwardly extending 90 brake rod 86, which in setting the 90 brakes, may be forwardly pulled by any of the usual mechanisms, used for such purpose.

As the brake shoes are so hung as to strike the hub 72 centrally with respect to 95 its height, the braking power will not be interfered with when the car is running light or heavily loaded and there will be no excessive wear on any part of the truck, such as is occasioned by the old method of 100 hanging and applying the brakes. As the usual brake beams are eliminated in this construction, there will be a great reduction in the weight. As the brake shoes are applied at the hub instead of at the tread of 105 the wheels, there will be less water, snow, dirt and ice picked up by the shoes, thus eliminating undue wear and liability of the 110 brakes freezing up. Thus greater mileage and a more effective brake effort will be obtained than is obtained with structures in which the brake shoes are applied to the 115 tread of the wheels.

From the above, it will be seen that owing to the manner of motor suspension, employed, and the rear truck being arranged to carry the greater part of the load, a maximum of braking efficiency is obtainable.

I do not limit my invention to the structure shown and described, as modifications, 120 within the scope of the appended claims, may be made without departing from the spirit of my invention.

What I claim is:—

1. A car body, two trucks centrally pivoted thereto, a single bearing on one truck centrally supporting said car body, and two bearings supporting said car body on the other truck.

2. A car body, two trucks centrally piv- 130

oted thereto, a single bearing on one truck centrally supporting said car body, and two bearings supporting said car body on the other truck, the truck carrying the two bearings being disposed so that it carries the greater portion of the load.

3. A car body, a truck, and oscillatory bearing means pivoted to swing on a horizontal axis on said truck and revoluble with respect to the car body and supporting the car body at two points at opposite sides respectively of said axis.

4. A car body, a truck, a bearing member pivoted to the truck on a horizontal axis, and two rollers supported by said member at opposite sides respectively of the axis thereof and supporting said car body.

5. A car body, a truck, two bearing members pivoted to the truck on a horizontal axis, and two pairs of rollers supporting said car body and respectively supported by said bearing members at opposite sides of said axis.

6. A car body having a curved track, a truck, a bearing member pivoted to the truck on a horizontal axis, and two rollers carried by said bearing member on opposite sides of said axis and supporting said track.

7. A car body, a truck centrally pivoted thereto, and bearing means pivoted to the truck on a horizontal axis and revoluble with respect to the car body and supporting the latter at two points disposed respectively at opposite sides of said axis.

8. A car body, a truck centrally pivoted thereto, a bearing member pivoted on a horizontal axis to said truck, and two rollers supporting said car body and supported by said member at opposite sides respectively of said axis.

9. A car body, a truck centrally pivoted thereto, two bearing members pivoted to the truck on a horizontal axis, and two pairs of rollers supporting said car body and respectively supported by said bearing members at opposite sides of said axis.

10. A car body, an axle, means including a helical suspension spring, having a vertical axis, for supporting the car body upon the axle, and normally inactive, means for assuming the functions of said suspension spring should the latter become inoperative.

11. A car body, an axle, and means including a helical suspension spring having a vertical axis and including a chain for supporting the car body upon the axle, the chain being normally inactive and having provision for assuming the function of the suspension spring should the latter become inoperative.

12. A car body, an axle, and means including a suspension spring and a supporting member for supporting the car body upon the axle, said supporting member being normally inactive and having provision for

assuming the function of the spring should the latter become inoperative.

13. A car body, an axle, and means including a suspension spring and a chain for supporting the car body upon the axle, the chain being normally inactive and having provision for assuming the function of the spring should the latter become inoperative.

14. A car body, an axle, an upper frame, a lower frame, bearing means pivotally supported on a horizontal axis on the lower frame and supporting said car body, a suspension spring suspending the lower frame from the upper frame, and means supported by the axle for supporting the upper frame.

15. A car body, an axle, an upper frame, a lower frame, bearing means pivotally supported on a horizontal axis on the lower frame and including two rollers supporting the car body and disposed respectively at opposite sides of said axis, resilient means supporting the lower frame from the upper frame, and means supported by the axle for supporting the upper frame.

16. A car body, an axle, an upper frame, a lower frame, bearing means pivotally supported on a horizontal axis on the lower frame and supporting said car body, resilient means supporting the lower frame from the upper frame, and means supported by the axle for supporting the upper frame.

17. A car, an axle, an upper frame, a lower frame, a bearing member pivotally supported on a horizontal axis on the lower frame, two rollers supporting said car body and supported by said member at opposite sides respectively of said axis, resilient means supporting the lower frame from the upper frame, and means supported by the axle for supporting the upper frame.

18. A car body, an axle, two frames, resilient means by which one frame is supported by the other, means for supporting one frame upon the axle, and bearing means pivoted on a horizontal axis upon the other frame and supporting and revoluble with respect to the car body.

19. A car body, an axle, two frames, resilient means supporting one frame upon the other, means for supporting one frame upon the axle, a bearing member pivoted on a horizontal axis upon the other frame, and two rollers supporting said car body and supported by said member at opposite sides respectively of said axis.

20. In a car, a car body, two trucks supporting the car body, one truck being disposed so as to carry a greater portion of the load and provided with two axles, two motors carried by the last named truck, and gearing connecting said motors with said axles respectively and exerting downward pressure thereon when the motors are operated to turn the axles in one direction.

21. In a car, a car body, two trucks supporting the car body, one being disposed so as to carry a greater portion of the load and having two axles, two motors carried by the last named truck, gearing connecting said motors with said axles respectively and exerting downward pressure thereon when the

motors are operated to turn the axles in one direction, and braking means carried by the last named truck and arranged to operate upon one of said axles.

In testimony whereof I have signed my name to this specification.

FRED STEFFENS.
